UNITED STATES PATENT OFFICE.

BENJAMIN D. UNDERHILL, OF NEW CANAAN, CONNECTICUT, ASSIGNOR TO DAVID S. PLUMB, OF NEWARK, NEW JERSEY.

METHOD OR APPARATUS FOR PRODUCING PICTURES IN COLORS.

1,340,923.

Specification of Letters Patent.

Patented May 25, 1920.

Application filed November 24, 1916. Serial No. 133,120.

To all whom it may concern:

Be it known that I, BENJAMIN D. UNDERHILL, a citizen of the United States, and a resident of New Canaan, county of Fairfield, 5 State of Connecticut, have invented certain new and useful Improvements in Methods or Apparatus for Producing Pictures in Color; and I do hereby declare the following to be a full, clear, and exact description 10 of the invention, such as will enable others skilled in the art to which it appertains to make and use the same.

This invention relates to method and apparatus for taking photographs for projection and for projecting such pictures in their natural colors, and has for its object 15 to provide a method for producing pictures of this character which may be carried out without the use of specially ground or reconstructed lenses or other expensive apparatus.

My invention is particularly applicable to the production of pictures in colors in which the colors are formed of two components 20 only, although the invention is applicable to the use of three colors also.

A further object of the invention is to provide an apparatus which may be used both for taking and projecting the pictures with 25 a simple change in the adjustment of the parts to adapt the apparatus for one purpose or the other.

A further object of the invention is to provide an apparatus of the character described by means of which identical views 30 may be simultaneously taken from points so little separated as not to produce a distinguishable difference in the pictures, whereby a perfect matching of the different 35 colored components of the picture may be secured.

With the above objects in view, my invention consists of the method and apparatus hereinafter described, taken in connection 40 with the accompanying drawings wherein I have illustrated a preferred form of optical system for carrying my method into effect.

In said drawings:

50 Figure 1 is a horizontal sectional view through an optical tube containing the elements arranged for taking pictures to be projected;

Fig. 2 is a similar view of the tube with

the optical elements arranged for projection;

Fig. 3 is an end elevation of the tube shown in Fig. 1 looking from the right;

Fig. 4 is a sectional view on line 4—4 of Fig. 1;

Fig. 5 is a sectional view on line 5—5 of Fig. 1;

Fig. 6 is a sectional view on line 6—6 of Fig. 1;

Fig. 7 is a horizontal sectional view of a modified arrangement of lenses adapted only for taking the pictures;

Fig. 8 is a similar view of a modified structure for projecting the pictures;

Figs. 9 and 10 are transverse sections on 70 the correspondingly numbered lines of Figs. 7 and 8, respectively;

Fig. 11 is a cross sectional view of a modified lens structure in which the lenses are cut to utilize the entire area of the diaphragm opening; and Fig. 12 is a similar view showing a similar modification in which three lenses are employed instead of 2.

Referring to the drawings, particularly 80 Figs. 1 to 6, 1 indicates a metal tube of ordinary character employed for lens mounts. Mounted in the tube 1 are two smaller tubes 2 and 3, the two smaller tubes fitting closely within the larger tube, the contacting faces 85 of the two smaller tubes being preferably ground away to reduce the thickness of the metal between the two tubes as much as possible. Each of the small tubes is equipped with suitable lenses 4 at each end, the lenses 90 of the two tubes being identical or of very slightly different focal lengths for the purpose hereinafter described. The lenses are ordinary photographic lenses and may be of any desired character, according to the 95 speed and definition required in the pictures, each tube considered alone being an ordinary photographic lens system.

The larger tube 1 is provided at each end with a stop preferably an iris diaphragm 5, 100 working as closely as possible against the ends of the small tubes. The small tubes 2 and 3 are each in two sections as shown, the two sections being separated by a third stop or iris diaphragm 7. Between the diaphragm 7 and the adjacent ends of the rear tube sections there is arranged a disk 8 of a diameter somewhat greater than twice the 105

diameter of the tube 1, the disk being mounted for rotary adjustment on a pivot 9 set in a reinforcing collar 10 surrounding the tube 1, and providing a support for the 5 diaphragm 7. Set in the disk 8 at spaced intervals equidistant from the center of the tube are a series of lenses 11 of different value, herein shown as four in number, the set consisting preferably of two negative 10 lenses of different power and two positive lenses of different power, whereby five different adjustments of the focal distance of the lens system are provided without moving the lens tube with relation to the film or 15 plate. The lenses 11 are each somewhat larger than the lenses of the small tubes and are so positioned in disk 8 that the center of the lens 11 in operative position will coincide with the line of contact of the two small 20 tubes 2 and 3. In addition to the four lenses set in the disk 8 there is provided an opening or blank 12 large enough to allow substantially the full diameter of the lens tubes to be unobstructed, as shown in Fig. 2, in which 25 figure the disk 8 is shown adjusted for projection.

The large tube 1 is provided at each end with slide carriers 13 and 14, respectively, here shown as fixed to the outer cover of 30 the iris diaphragms 5. The slide carriers are preferably stamped out of sheet metal and are of the usual rectangular shape open at one side. The purpose of the slide carriers is to provide support for prismatic 35 lenses 15 mounted as shown in detail in Fig. 6 for rotation in a square frame 16 fitting in the slide carrier by which the centers of the prismatic lenses will be maintained in line with the centers of the small tubes. Each 40 prismatic lens is supported in a half ring 17 having gear teeth formed on its outer periphery and positioned to mesh with a rack 18 slidingly mounted in the frame 16.

When the lens system is used on a camera 45 the prismatic lenses are placed in the slide carrier at the end toward the film to deflect the light rays through the two lens systems away from each other so that the centers of the exposed areas forming the two pictures 50 will be separated to a greater extent than the centers of the uncovered portions of the lenses. In projecting the pictures the prisms are placed in their slide carrier at the outer end of the lens tube to provide a 55 convenient means for superimposing the pictures on the screen in exact registration with each other.

Attached to the flange of the rear slide carrier 14 is a tubular extension 20 of the 60 full diameter of the tube 1, by means of which the lenses may be detachably mounted for telescopic adjustment in the fixed tube sections 21 with which the camera and the projection machine will be provided.

65 The slide carrier 13 at the outer end of

the tube 1 is shaped to receive and support the frame of a light filter 22 comprising a pair of glass plates supporting between them two differently colored pieces of gelatin such as commonly employed for light filters in color photography work. It will of course be understood that one color of gelatin completely covers one of the small tubes and the other piece completely covers the other tube, and that the colors selected will 70 be the so-called 2 color opposites which have heretofore been employed for like purpose.

In Fig. 1 I have shown the optical elements arranged for taking pictures. For this purpose the several diaphragms 5 and 7 80 are adjusted so that the diaphragm openings are no greater than the distance between the centers of the two small tubes whereby only a portion of the adjacent halves of the lenses at the ends of the small 85 tubes are uncovered, as more clearly shown in Fig. 3. The frame 16 carrying the prismatic lenses is placed in the slide carrier 14 at the rear end of the large tube 1, and the color filter is supported on the slide carrier 90 at the opposite end of the large tube 1. The color filter may be arranged at the other end of the lens tube if desired, or in front of the film in the camera.

The disk 8 is adjusted to bring the proper 95 lens into adjustment with the proper lenses of the tube to focus the object desired to be photographed on to the film at the back of the camera. The exposure will now be made with the ordinary shutter mechanism of a 100 moving picture camera. By screening down the lenses in the manner shown with the adjustable diaphragms, the pictures are taken from points so little separated as to produce substantially identical images through 105 the two lens systems. Without the prisms at the ends of the small lens tubes the individual pictures on the screen are limited in size to the distance between the centers of the lenses or to substantially the same area 110 as the diaphragm openings, but with the prisms the rays of light through the different lenses may be diverged to any extent desired by rotating the prisms to bring their thinnest portions more or less to the plane 115 of the optical axes of the two lens systems.

When the picture is projected the elements of the optical system are arranged in the manner shown in Fig. 2. The prismatic lenses are placed in the slide carrier 13 at 120 the front end of the optical tube immediately behind the color filter. The various diaphragms are open to their full extent and the disk 8 is adjusted to bring the opening 12 into position for the two small tubes to be unobstructed for the full diameter of the lenses. The positive film printed from the negative taken with the parts adjusted as previously described, is fed through the machine in the usual manner, each pair of 125 130

5 pictures being simultaneously projected through the two lens systems. During the projection of the picture the lens may be focused by adjusting the tube 1 in and out 5 in the tube section 21. The lens system of each small tube projects the picture on the corresponding side of the film to the screen to occupy substantially the full area of the screen, the two pictures probably mismatching 10 slightly if projected without the correcting prisms.

As the pictures are taken from points having but little separation due to the small area of the diaphragm opening, the two pictures 15 will be substantially identical instead of presenting the differences of a stereoscopic pair taken with lenses separated to the full extent of the optical axis of the two tubes. By using the prismatic lenses at the 20 front end of the tube during the projection, and adjusting them so as to effect a very slight deflection of the light rays, the slight mismatching may be completely corrected and the two pictures accurately superposed 25 to give a sharp picture of excellent definition and without the differently colored border heretofore unavoidable when two simultaneously taken pictures are projected on the screen.

30 In taking the pictures the small exposed portion of each lens has the same effect as a large lens when the diaphragms are open. That is, the picture produced is the same as far as focus, etc., is concerned, but the appearance 35 of the two pictures considered with relation to the point from which taken is the same as if the lenses had their geometrical centers at the center of the exposed portion of the lens, so that by this arrangement I am able to use lenses of fair 40 size which can be accurately ground and matched, and at the same time secure all the advantages of closely positioned lenses of very minute diameter.

45 I have shown the prismatic lenses, the focusing lens carrier and the diaphragm as arranged for adjustment in order that the same lenses may be used for taking and projection. In commercial use separate systems 50 will more conveniently be employed for the camera and the projector, and each system may have its prisms permanently fixed in place or the prisms may be dispensed with. This adjustment or some other mechanism 55 for the same purpose is, however, preferable in projection for securing accurate matching of the pictures.

60 In Fig. 7 I have illustrated an arrangement of lenses, etc., adapted solely for taking pictures in accordance with my improved method, whereby the structure is much simplified. As here shown, the two lens systems are supported in an outer casing 59, which may be of elliptical cross section as shown in Fig. 9, the two lens tubes be-

ing fixed in place with their adjacent edges in close contact. Preferably the metal of the tube is cut away or left very thin on the adjacent sides of the lens tubes so that the optical centers of the lenses may be brought as 70 close together as possible. In the drawings I have shown the lens tubes as complete throughout their circumference, but they may be cut away as described, or part of the glass of each lens may be sawed off on adjacent sides as shown more particularly in Fig. 11 so that the entire area of the opening in the diaphragm 51 is backed by a portion 75 of the lenses.

The edge of the opening in the diaphragm 80 51 should coincide substantially with the optical centers of the lenses, and the diaphragms may each be formed of a single piece of sheet metal with a fixed opening instead of the iris diaphragm of the previously 85 described construction.

Each lens tube is divided in two sections to provide for an interposed disk 52 mounted for rotation on a pin 53 supported by a bracket 54 attached to one of the curved 90 side edges of the elliptical casing 50. The disk 52 carries a series of focusing lenses 55 as shown in Fig. 9 whereby the lens system may be supported in fixed relation to the plane of the plate or film upon which the 95 photograph is to be taken.

The rear ends of the front sections of the lens tubes are closed by a middle diaphragm plate 56 having a central aperture equal in size to the aperture of the diaphragm 51 and 100 mounted in each rear section of the lens tubes is a sheet metal web or shield 57, each of which is cut away on its inner side to expose a portion of the rear lens corresponding in shape and area with the exposed 105 portion of the front lenses. Fixedly supported in the casing back of the lens tubes are a pair of prisms or prismatic lenses 58 with their inner edges adjacent, to produce a divergence of the images formed by the 110 two separate lens systems, and back of the prismatic lenses and also fixed in the casing 50 is a frame 59 supporting the color filters of substantially complementary colors, whereby the exposures made through one 115 lens system will have a different color value from the exposures effected through the other lens system.

A separate web or division plate as shown in Figs. 1 and 2 will of course extend from 120 the color filters into the camera in close proximity to the film, so that each side of the film will be exposed only to the light rays through the lens system and color filter along that side.

125 It will of course be understood that a camera equipped with my improved lens system will be supplied with the usual shutter, film feed and other accessories necessary for the proper exposure or manipula- 130

tion of the plate or film as the case may be. With the lens system arranged only for the taking of pictures, all the adjustable parts except the focusing disk 52 are dispensed 5 with in order to thereby much simplify the apparatus and reduce its cost of manufacture and liability to derangement in the hands of inexperienced operators. The focusing disk will contain five or more 10 lenses of different focus whereby upon determining the approximate distance of the principal object in the field to be photographed the lens disk will be adjusted to bring the proper lens into action. Also, 15 the prisms 58 may be dispensed with if desired, but their use is advantageous in that with the other elements of the system the same, larger pictures may be taken as explained above.

20 Pictures taken with the above described lens system may be projected with a projecting apparatus equipped with the lens arrangement of Fig. 2, but I prefer to provide a simpler arrangement of the lenses 25 when the projector is not adapted for use alternately as a camera. A lens system of this character as illustrated in Fig. 8 comprises outer elliptical casing 60 in which are supported for lateral movement 30 toward and away from each other two lens tubes 61, each of which is equipped with two or more lenses forming a complete lens system for projection. The lens tubes 61 are adjusted and maintained in adjusted 35 position by means of a screw 62 having oppositely threaded portions working in correspondingly threaded ears 63 projecting respectively from the two lens tubes through suitable slots 64 in the upper side 40 of the elliptical casing 60. The screw 62 is mounted for rotation in a fixed projection 65 on the casing 60 between the pins 63, the screw being held against longitudinal movement by a pin and groove bearing 65.

45 By rotating the screw in either direction by means of the knurled thumb piece attached to one end, the lenses will be shifted toward and away from each other while maintaining their centers equidistant from 50 the center of the elliptical casing.

I have shown the casing 60 as also equipped with prisms 66 at its outer end, the prisms being arranged with their thin edges adjacent to effect a lateral deflection 55 of the light rays to assist in superimposing the two pictures on the screen. These prisms may, however, be dispensed with and the entire matching of the pictures effected by the lateral adjustment of the two 60 lens tubes toward and away from each other. If prisms are used a smaller lateral adjustment of the two lens tubes will be necessary to effect a proper registration of the pictures. The color filter 67 will be 65 mounted in the usual manner on the front

end of the casing 60, to give the proper color values to the light rays through the two lens systems so that the composite picture will appear in substantially its natural colors.

70

In projecting, the lens is preferably focused by altering its position instead of by interposing lenses of different values in the system. For this purpose the tube 60 is supported in a casing 68 fixed to the 75 front wall 69 of the projecting machine, the two parts being connected by a suitable rack and pinion 70 whereby the tube may be readily adjusted into and out of the casing 68.

80

I have shown and described the lenses employed in carrying out my invention as circular and with thin tubes on their adjacent sides to allow their being placed close together. I may, however, with advantage cut away a portion of the glass also on the adjacent edges of the lenses as shown in Fig. 11, so that the portion of the lens exposed by the opening in the diaphragm will be semi-circular instead of generally elliptical as where the circular lenses are used.

85

As shown in Fig. 11, the lens tube 61* and the lenses 61^b are cut away on their meeting faces sufficiently to provide flat surfaces equal in length to the diameter of the diaphragm opening, whereby the exposed area of the lens will be semi-circular as described. In each case the edge of the diaphragm opening will intersect the optical 100 centers of the lenses so that with the diaphragm opening of the same size the images formed will be substantially the same whether the lenses are cut away on their adjacent edges or not, but when they are 105 cut away, the lenses will have an effective area of greater size and consequently will transmit more light or be more "rapid" in their action.

95

I have shown and described my improved 110 method as adapted for a two-color system of color photography, but the invention may be adapted for a three-color system, such, for example, as described in the patent to Holbrook, No. 1,151,786, of August 31, 1915.

115

In Fig. 12 I have indicated diagrammatically a suitable arrangement of lenses for the purpose. As here shown, the outer casing 70 is circular and contains three small lens tubes which may be arranged with the two upper ones parallel and horizontal, and the lower one with its center equidistant from the centers of the two upper lenses. A diaphragm 72 having a central circular opening covers one end of the casing 70, the edges of the diaphragm opening preferably registering with the optical centers of the lenses.

120

The various lenses may be uncut, that is, circular in shape, as in the construction illus- 125

130

trated in Figs. 1 and 2, but I prefer to cut away the meeting edges of the three lenses and their tubes as shown in Fig. 12 so that the edges of three lenses meet in the center 5 of the diaphragm opening.

In other respects the three-color system will be similar to the two-color system previously described. The focus may be secured by a focusing disk having lenses of 10 different values somewhat larger than the diaphragm opening and the lens tubes may or may not be provided with prisms. When prisms are used the prisms of the lower lens will be arranged to deflect the rays downward to increase the area of the field. Of course, when three color filters are used the colors will be the shades for the well known 15 three-color systems.

One advantage that may be mentioned in 20 providing separate lenses for the three-color system instead of a single lens made of the reversed sectors, as in the Holbrook patent is that the lenses of the three separate tubes may be of slightly different values to 25 compensate for the different lengths of the light rays of the different component colors, the longer red rays through the red filter requiring a slightly longer focal length of lens to secure an exact focus than the rays of 30 shorter wave length through the other filters.

Further, in using separate lenses, each lens may be mounted in a separate tube and the 35 three tubes fitted in the outer casing, the smaller tubes being cut away through such a small portion of their complete circumference as to form rigid supports for the lenses when merely assembled and clamped in the

outer casing. When the lens is made up from reversed sectors, the parts have to be 40 very carefully matched and mounted as a single lens, the operation being both expensive and difficult.

I claim:

1. The method of producing projected 45 colored pictures which consists in photographing the view to be projected through two separate optical systems having color screens of different colors and with their optical axes parallel and closely adjacent and 50 with only adjacent portions of said lenses exposed to the light rays, deflecting the light rays forming each view away from each other to increase the distance between the centers of the pictures and then projecting 55 the pictures so produced through corresponding color screens and in superimposed relation through lens systems having a greater separation between the centers of 60 their exposed areas than between the centers of the exposed areas of the taking lenses.

2. An apparatus for taking pictures for color projection or projecting such pictures comprising a pair of substantially identical lens systems mounted closely adjacent and 65 in parallel relation, each lens system having only the portion to the side of its optical system adjacent the other lens system effective, and differently colored light filters in 70 each system, said systems including a series of lenses of different power to be interchangeably interposed in the systems to vary the focus of the systems as a whole.

In testimony whereof I affix my signature.

BENJAMIN D. UNDERHILL,
